UNITED STATES PATENT OFFICE.

STANLEY M. UDALE, OF DETROIT, MICHIGAN.

VAPORIZER.

Application filed March 14, 1921, Serial No. 452,053. Renewed June 9, 1924.

To all whom it may concern:

Be it known that I, STANLEY M. UDALE, a citizen of the United States, and residing at Detroit, in the county of Wayne and State 5 of Michigan, have invented a new and Improved Vaporizer, of which the following is a specification.

My invention relates to improved means 10 of vaporization for internal combustion engines whereby the vaporized fuel is admitted adjacent to the inlet valve of an internal combustion engine.

Fig. 1 shows diagrammatically the improved means for vaporization.

Fig. 2 shows the device applied to an internal combustion engine.

Description.

In Fig. 1 A' is the float chamber supplying fuel to the fuel nozzle B' which delivers into the smaller conduit C'. This conduit leads into the larger conduit F' at the throat of the venturi D' and D'' when the rich mixture delivered from C' is diluted by air 25 admitted by the throttle E' into the larger conduit F'. The conduit C' lies within the exhaust jacket G' which thereby heats the fuel drawn through C' and causes vaporization to take place before the fuel issues into 30 D'. Compensating means are provided in the form of the tube H' which leads from the inlet manifold F' to the float chamber A'. The outlets L' and L'' of the conduit C' adapt the device for use with a four 35 cylinder engine of orthodox design.

In Fig. 2 the same letters without the prime refer to similar parts in Fig. 1. An inlet valve of the engine is shown at K and the exhaust valve at J.

Operation.

On closing the throttle when running slowly considerable suction is developed in the tube C' which causes fuel to be aspirated 45 from the nozzle B'. In order to prevent excessive fuel being aspirated the compensating tube H' equalizes the pressure in the float chamber A' and the inlet manifold F' in the well known manner. Any other well 50 known means of compensation may be substituted for the equalizing tube H' without departing from the scope of my invention. On opening the throttle the pressure in the float chamber A' increases as the vacuum in 55 the inlet manifold F' decreases and the increased flow of fuel through the venturi D'

causes an increased flow of fuel through the vapor tube C' thereby delivering an increased quantity of vapor, thus compensating for the increased amount of vapor admitted by the throttle E'.

When an automobile is running at from fifteen to twenty miles an hour, at which speeds fuel economy is commercially most valuable, the phenomenon known as stratification occurs in the cylinders of engines embodying the present invention, by reason of the fact that the pure air within the intake manifold is first drawn into the engine cylinder and is subsequently followed by 70 the vaporized fuel and rich mixture from the rich-mixture outlet L. The beneficial results of stratification in increasing mileage are well known, the explanation generally adopted being that it enables a higher compression to be carried for a given power development. That is to say, there is a cushion of air next above the piston, above which cushion lies the comparatively rich mixture which is sufficiently diluted by the 80 fuel air to be explosive. The increase in fuel economy thereby obtained is quite large.

I claim:

1. In a vaporizer for supplying fuel to internal combustion engines, the combination of a fuel receptacle and a fuel nozzle connected thereto, means for mixing air with the fuel at said nozzle, an exhaust passage for the engine, an intake manifold for the engine having discharge openings and an air inlet, a throttle valve in said air inlet, and a fuel passage leading from the fuel nozzle through the exhaust passage and then forking, one branch extending to each discharge opening of the intake manifold.

2. In a vaporizer for supplying fuel to internal combustion engines, the combination of a fuel receptacle and a fuel nozzle connected thereto, means for mixing air with the fuel at said nozzle, an exhaust passage for the engine, an intake manifold for the engine having discharge openings and an air inlet, a throttle valve in said air inlet, and a fuel passage leading from the fuel nozzle through the exhaust passage and then forking, one branch extending to each discharge opening of the intake manifold, said intake manifold being formed with venturis at the discharge ends of the branches of the fuel passage.

3. In a vaporizer for supplying fuel to internal combustion engines, the combination

of a constant level fuel reservoir and a fuel nozzle connected therewith, an exhaust passage for the engine, a rich-mixture passage leading from the fuel nozzle through the exhaust passage, a pure-air intake manifold having discharge openings at the engine and an air inlet, a throttle valve in said air inlet,

the outlets of the heated rich-mixture passage being located solely in each of the discharge openings of the inlet manifold whereby the outlets for the heated rich mixture are subjected to the full suction of the engine.

STANLEY M. UDALE.
